UNITED STATES PATENT OFFICE

VICTOR KENNEY, OF NEW YORK, N. Y.

EYELASHES FOR DOLLS

Application filed February 20, 1930. Serial No. 429,842.

This invention relates to new and useful improvements in artificial eye lashes for dolls.

The invention has for an object the provision of a device of the class mentioned which is of simple durable construction, dependable in use and efficient in action, and which can be manufactured and sold at a reasonable cost.

10 The invention proposes in combination with a doll's head having slits over its eyes extending thru a knitted fabric and form constituting the doll's head, eye lashes held in and extending thru said slits and 15 consisting of a plurality of hair strands arranged in line, bound together at their inner ends and engaging in metallic tape sheets adapted to maintain bent positions for changing the tilt of the eye lashes, and 20 the edges of said tape sheets slightly projecting from the outer surface of the doll's head to permit bending.

For further comprehension of the invention, and of the objects and advantages 25 thereof, reference will be had to the following description and accompanying drawings, and to the appended claims in which the various novel features of the invention are more particularly set forth.

30 In the accompanying drawing forming a material part of this disclosure:—

Fig. 1 is a perspective view of a doll's head provided with eye lashes according to this invention.

35 Fig. 2 is an enlarged fragmentary detailed view of a portion of Fig. 1 showing the eye lashes in detail.

Fig. 3 is a perspective view of Fig. 2.

40 Fig. 4 is an enlarged fragmentary sectional view taken on the line 4—4 of Fig. 1.

Fig. 5 is a view similar to Fig. 4 but of modified form.

45 Fig. 6 is a view similar to Fig. 2, but illustrating a modification of the invention.

Fig. 7 is a fragmentary sectional view taken on the line 7—7 of Fig. 6.

Fig. 8 is a fragmentary sectional view taken on the line 8—8 of Fig. 7.

50 Fig. 9 is a fragmentary enlarged detailed

view of the metallic tape sheet holding the hair strands in place.

Fig. 10 is a fragmentary sectional view taken on the line 10—10 of Fig. 9.

On the drawing a doll's head 12 has been 55 shown consisting of a knitted fabric 13 and an inner form 14. This doll's head is provided with slits 15 over the eyes along a line customarily provided with eye lashes. The artificial eye lashes for the doll's head 60 consists of eye lashes 16 held in and extended thru said slits 15 and consisting of a plurality of hair strands 17 made of hair, cotton, wool or any other suitable substance arranged in a line, bound together at their 65 inner ends 18 and engaging in metallic tape sheets 19 adapted to maintain bent positions for changing the tilt of the eye lashes, and the edges 20 of the said tape sheets 70 slightly project from the outer surface of the doll's head to permit bending.

The eye lashes 16 are held in place on the form by glue 21. This glue is arranged on the inside of the form and acts between the form and the inner end of the eye 75 lashes, thus accomplishing the securing. The line in which the hair strands are arranged to simulate the eye lashes is of arcuate shape corresponding with the outer shape of such lashes. This may be seen from an inspection of Figs. 1 to 3 inclusive. The binding of the hair strands at their inner ends consists of a cloth tape 22 glued or otherwise attached on the inner ends 18 of the hair strands. This cloth tape is bent along its 80 center line so that its edges 23 are superimposed and the hair strands are arranged between the two portions of the tape.

The metallic tape sheets 19 are also bent along their center lines 24 so that the edges 90 25 are superimposed to each other. The metallic tape sheets are arranged over the cloth tape and preferably are of a size so that its edges are superimposed upon the edges 23 of the cloth tape. These tape sheets 95 should be of soft metal so that they are adapted to maintain positions into which they are bent for changing the tilt of the eye lashes. In Figs. 4 and 5, dot and dash lines 26 indicate a bent position of the ex- 100

tended portions of the metallic tape so that the eye lashes are held in a different inclined position.

In Fig. 5, a modified form of the device has been illustrated which particularly differs from the previous form in the manner of holding the eye lashes in the said slits 15. This is accomplished by the rear edge 24 of the metallic tape being bent at right angles to the other portion so that when engaged thru the slit, it may rest flush against the inner side of the form 14. The holding is then supplemented with glue 21 which combines the form and the metallic tape together. The front edge 20 of the metallic tape projects slightly from the fabric 13 so that they may be bent to change the tilt of the lashes.

In Figs. 6 and 7, another form of the invention has been illustrated in which the eye lashes 16 are secured upon the outer surface of the fabric 13 by lugs 27 projecting from the ends of the metallic tape and passing thru openings in the form so as to extend into the latter element. The inner ends 28 of the lugs are bent so as to maintain the position of the eye lashes. The metallic tape has its rear edge 24 bent at right angles to the other portion and this rear edge is arranged flat against the outer side of the fabric 13. The inclination of the eye lashes 16 may be changed by bending the horizontal portion of the tape slightly upwards or downwards. In other respects this form is similar to the ones previously described.

In Figs. 9 and 10, a detail has been shown of the metallic tape sheets 19. This detail particularly shows the construction of the front edges 25. In the vicinity of these front edges the metallic tape is formed with longitudinal grooves 30 parallel to each other and extending the full length of the tape. These grooves facilitate bending of the projecting ends 20 of the tape so as to hold the eye lashes at different tilted positions. Preferably a pair of pliers should be used for accomplishing the bending.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. In combination with a doll's head having slits over its eyes extending thru a knitted fabric and form constituting the doll's head, eye lashes held in and extending thru said slits and consisting of a plurality of hair strands arranged in a line, bound together at their inner ends and engaging

in metallic tape sheets adapted to maintain bent positions for changing the tilt of the eye lashes, and the edges of said tape sheets slightly projecting from the outer surface of the doll's head to permit bending.

2. In combination with a doll's head having slits over its eyes extending thru a knitted fabric and form constituting the doll's head, eye lashes held in and extending thru said slits and consisting of a plurality of hair strands arranged in a line, bound together at their inner ends and engaging in metallic tape sheets adapted to maintain bent positions for changing the tilt of the eye lashes, and the edges of said tape sheets slightly projecting from the outer surface of the doll's head to permit bending, the binding together of the hair strands at their inner ends being accomplished with cloth tape bent along its central line so that its edges are superimposed, said hair strands being engaged between the portions of said cloth tape, and said metallic tape sheets being engaged over said cloth tape.

3. In combination with a doll's head having slits over its eyes extending thru a knitted fabric and form constituting the doll's head, eye lashes held in and extending thru said slits and consisting of a plurality of hair strands arranged in a line, bound together at their inner ends and engaging in metallic tape sheets adapted to maintain bent positions for changing the tilt of the eye lashes, and the edges of said tape sheets slightly projecting from the outer surface of the doll's head to permit bending, said metallic tape sheets being of soft metal to maintain positions into which it is bent.

4. In combination with a doll's head having slits over its eyes extending thru a knitted fabric and form constituting the doll's head, eye lashes held in and extending thru said slits and consisting of a plurality of hair strands arranged in a line, bound together at their inner ends and engaging in metallic tape sheets adapted to maintain bent positions for changing the tilt of the eye lashes, and the edges of said tape sheets slightly projecting from the outer surface of the doll's head to permit bending, said metallic tape sheets having their rear edges bent at right angles to the front portion so as to rest against the doll's head.

5. In combination with a doll's head having slits over its eyes extending thru a knitted fabric and form constituting the doll's head, eye lashes held in and extending thru said slits and consisting of a plurality of hair strands arranged in a line, bound together at their inner ends and engaging in metallic tape sheets adapted to maintain bent positions for changing the tilt of the eye lashes, and the edges of said tape sheets slightly projecting from the outer surface of the doll's head to permit bending, the

metallic tape sheets being formed with longitudinal parallel grooves along its front edges for aiding in the bending to change the tilt of the eye lashes.

In testimony whereof I have affixed my
5 signature.

VICTOR KENEY.
